CLAIM

The ornamental design for a wall-mounted shelf, as shown and described.

DESCRIPTION

FIG. 1 is a perspective view of the wall-mounted shelf of the present invention;

FIG. 2 is a front elevation view of the wall-mounted shelf shown in FIG. 1;

FIG. 3 is a rear elevation view of the wall-mounted shelf shown in FIG. 1;

FIG. 4 is a left elevation view of the wall-mounted shelf shown in FIG. 1;

FIG. 5 is a right elevation view of the wall-mounted shelf shown in FIG. 1;

FIG. 6 is a top plan view of the wall-mounted shelf shown in FIG. 1; and,

FIG. 7 is a bottom plan view of the wall-mounted shelf shown in FIG. 1.

The broken lines illustrated in FIGS. 3 through 5 illustrate features of the present invention and form no part of the claimed design.

1 Claim, 5 Drawing Sheets
